DESIGN FOR A TRAILER TANK VEHICLE BODY

Joseph M. Kramer and Hugh A. Mullin, Kansas City, Mo., and William H. Graves, Kansas City, Kans., assignors to Andrew A. Kramer, Kansas City, Mo.

Application September 20, 1935, Serial No. 58,630

Term of patent 14 years

To all whom it may concern:

Be it known that we, Joseph M. Kramer and Hugh A. Mullin, citizens of the United States, residing at Kansas City in the county of Jackson and State of Missouri, and William H. Graves, a citizen of the United States, residing at Kansas City, in the county of Wyandotte and State of Kansas, have invented a new, original, and ornamental Design for a Trailer Tank Vehicle Body, of which the following is a specification, reference being had to the accompanying drawing forming a part thereof.

In the drawing:

Figure 1 is a perspective view of our new design, and

Figure 2 is a top plan view thereof.

The dominant features of the design reside in the design of the rear end portion of the tank body and the ornamentation along the top thereof.

We claim:

The ornamental design for a trailer tank vehicle body substantially as shown and described.

JOSEPH M. KRAMER.

HUGH A. MULLIN.

WILLIAM H. GRAVES.
